(57) **CLAIM**

The ornamental design of a hood for drum sander, as shown and described.

DESCRIPTION

FIG. 1 is an environmental perspective view taken from the front, top, left-hand side of a hood for drum sander, showing the hood in use on a drum sander;

FIG. 2 is a perspective view taken from the front, top, left side of the hood for drum sander;

FIG. 3 is a perspective view taken from the front, bottom, left side thereof;

FIG. 4 is a front elevational view thereof;

FIG. 5 is a rear elevational view thereof;

FIG. 6 is a side elevational view from the left side thereof;

FIG. 7 is a side elevational view from the right side thereof;

FIG. 8 is a top plan view thereof; and,

FIG. 9 is a bottom plan view thereof.

In the drawings, the broken lines depict environmental elements and portions of the article that form no part of the claimed design.
